UNITED STATES PATENT OFFICE.

ARTHUR G. ROGERS, OF MERIDEN, CONNECTICUT, ASSIGNOR TO C. ROGERS & BROS., OF SAME PLACE.

DESIGN FOR A SPOON OR FORK HANDLE.

SPECIFICATION forming part of Design No. 19,841, dated May 13, 1890.

Application filed March 24, 1890. Serial No. 345,168. Term of patent 14 years.

To all whom it may concern:

Be it known that I, ARTHUR G. ROGERS, of Meriden, in the county of New Haven and State of Connecticut, have invented a new Design for Spoon and Fork Handles, (B;) and I do hereby declare the following, when taken in connection with accompanying drawings and the letters of reference marked thereon, to be a full, clear, and exact description of the same, and which said drawings constitute part of this specification, and represent a face view of a fork, illustrating the spoon in broken lines.

This invention relates to a design for the ornamentation of the handles of spoons, forks, and like articles; and the design consists in the ornamentation, as shown in the accompanying illustration and hereinafter described.

Midway of the length of the handle is a boss *a*, from which toward the bowl the shank *b* of the handle is of substantially equal width. The face of the shank is ornamented by the representation of a series of ribs running

from a central line on the shank obliquely in opposite directions to each end of the shank. From the boss *a* the tip *d* extends, gradually increasing in width, to the end, which is of substantially semicircular shape. On the face of the tip is the representation of a series of scrolls *e* springing from one side and extending across to the opposite side. The space between the scrolls and at the tip above the scrolls is represented as ornamented; but this ornamentation may be omitted, as also the ornamentation of the shank, the essential feature of the design being the representation of a series of scrolls on the tip portion of the handle.

I claim—

The design for spoon and fork handles, as herein shown and described.

ARTHUR G. ROGERS.
